PAGE 3

Fig. 3.

Fig. 4.

Fig. 5.

Figure 1 is a front perspective view of a portable electric saw embodying my new design;

Figure 2 is a rear perspective view thereof;

Figure 3 is a left side elevational view of a portable electric saw;

Figure 4 is a front elevational view of a portable electric saw; and

Figure 5 is a rear elevational view thereof.

The dominant features of my design reside in those portions thereof shown in full lines.

I claim:

The ornamental design for a portable electric saw, as shown and described.
